UNITED STATES PATENT OFFICE.

ANDREW GEYER, OF CAMBRIDGE, MASSACHUSETTS.

DESIGN FOR A NURSING-BOTTLE.

SPECIFICATION forming part of Design No. 18,420, dated July 3, 1888.

Application filed April 23, 1888. Serial No. 271,645. Term of patent 7 years.

To all whom it may concern:

Be it known that I, ANDREW GEYER, a citizen of the United States, and a resident of Cambridge, in the county of Middlesex and State 5 of Massachusetts, have invented and produced a new and original Design for Nursing-Bottles, of which the following, taken in connection with the accompanying drawings, is a specification.

10 Figure 1 is a side elevation of my newly-designed nursing-bottle; Fig. 2, a rear or bottom view of the same; and Fig. 3, a plan view thereof, these three views being deemed necessary to fully illustrate my design.

15 *a* is the body of the bottle, which is circular in form, as more fully shown in Fig. 2. Said body has on one side a flattened surface, *a'*. (Shown in Figs. 1 and 2.) In addition to such flattened side the bottle has at its end another 20 flattened surface or base, *a''*, as shown in the drawings.

a' is the neck of the bottle, that is bent or inclined upward at an angle or slight curve to the flattened surface *a'*, as shown in Fig. 1.

b is the nipple, as usual.

The leading feature of my design is a bottle of circular shape having one flat side, a flat end, and an inclined or curved neck, as above described, and as shown in the accompanying drawings.

25 I claim—

The design for a nursing-bottle herein shown and described, the same consisting of a bottle having the circular body *a*, the flattened side *a'*, the flattened end *a''*, and the inclined or 30 curved neck *a'*, all combined and shaped substantially as set forth.

In testimony whereof I have signed my name to this specification, in the presence of two subscribing witnesses, on this 19th day of April, 40 A. D. 1888.

ANDREW GEYER.

Witnesses:

ALBAN ANDRÉN,
HERBERT L. CHAPIN.
